UNITED STATES PATENT OFFICE.

HOWARD H. SHELTON, OF AKRON, OHIO.

DIE FOR FORMING COTTERS.

1,151,411.

Specification of Letters Patent. Patented Aug. 24, 1915.

Application filed January 29, 1915. Serial No. 5,126.

To all whom it may concern:

Be it known that I, HOWARD H. SHELTON, a citizen of the United States, residing at Akron, in the county of Summit and State 5 of Ohio, have invented new and useful Improvements in Dies for Forming Cotters, of which the following is a specification.

This invention relates to improvements in dies for forming cotters from suitable 10 blanks, and the object of the invention is to provide a die by which cotters completely fashioned may be formed thereby.

Briefly, the manufacture of cotters heretofore has necessitated the employment of a 15 plurality of operations or manipulations on the blanks before a marketable cotted was produced, each operation requiring the use of a special die or a special tool therefor, but by the use of the die which forms the 20 subject matter of this invention, cotters faultlessly formed are produced in one operation by simply forcing suitable blanks through them.

With the foregoing and other objects in 25 view, the invention consists in the novel construction, combination and arrangement of parts constituting the invention to be hereinafter specifically described and illustrated in the accompanying drawings which form 30 a part hereof wherein is shown the preferred embodiment of the invention, but it is to be understood that changes, variations and modifications can be resorted to which come 35 within the scope of the matter hereinafter claimed.

In the drawings in which similar reference numerals indicate like parts in the different figures, Figure 1, is a perspective view of a die embodying this invention; Fig. 2, is a 40 similar view of the die and a blank in position with respect to the die and ready to be forced therethrough; Fig. 3, is a perspective view of a portion of one member of a die when the die is made up of a plurality 45 of parts; Fig. 4, is a view of a die and a blank, the latter being positioned in the die and partially formed; and, Fig. 5, is a view of a finished cotted produced by the die shown in Fig. 1.

50 The die forming the subject matter of this

invention, is for ease of manufacture preferably made up of two members 1 and 2 adapted when assembled by being clamped together, to form a complete die. Each of the members is fashioned in the general 55 form of a rhombohedron, and suitable means, such for instance, as dowel-pins, (not deemed necessary to illustrate) are employed to secure their perfect registration, but on the other hand the die may be formed of a 60 single piece of material with the die opening solely in the single piece without departing from the scope of this invention. The members 1 and 2 are preferably provided with front and rear parallel faces 3 65 and 4 and inclined parallel upper and lower faces 5 and 6. The top and bottom faces are preferably provided with portions 7 beveled with respect to the inclined portions and lying in planes perpendicular to the front 70 and rear faces 3 and 4. In the upper and lower faces 5 and 6 are formed die openings which may be in the case where the die is made up of two portions, as shown in the drawings, partially formed in each of the 75 members, and are numbered respectively 8 and 9, the side walls of which are preferably approximately parallel with the exit end 10 of the opening 8 terminating at the rear face 4 and with the corresponding portion 80 11 of the opening 9 in the lower face 6 terminating at the front face 3 so that the openings are reversely arranged at opposite ends of the die body and in opposite faces thereof, but with the axes of the openings 85 approximately parallel with each other and perpendicular to the front and rear faces 3 and 4. The positioning of the die opening at the opposite ends of the members is simply done for the sake of economy, so that 90 both ends of the die may be utilized by merely reversing the die before use and also if desired, the openings at opposite ends of the die may vary as to size, to the end that a single die may be used for producing 95 cotters of different sizes by reversing it.

In forming the openings 8 and 9 when the die is composed of separate members, as shown in the drawings, the opposing faces of the ends of the members are provided with 100

5 oppositely-disposed grooves 16 so fashioned that when the members are clamped together or assembled the walls of the grooves provide die-openings of the desired configuration and obviously a die opening of the same efficiency could be produced if the openings were formed in a single integral block or piece of metal.

10 Irrespective of the question of the formation of the die, whether of two members or of a single piece, or whether the die member is provided with die openings at opposite ends, the die is provided with a forming portion consisting of an approximately cylindrical opening extending throughout 15 with the entrance end of the opening outwardly flared and having its origin in one inclined end at approximately the latter's junction with one side of the member 20 and its exit end terminating at the opposite side at a point removed from the end thereof. The side walls forming the openings are approximately parallel and the exit end being of a size approximately corresponding to the rounded head portion of 25 the cotter to be made therein. Extending from the ends of the body portion of the die to and communicating centrally with the exit ends of the die openings 30 are slots 18, which are produced by cutting away sufficient portions of the narrow necks of metal existing between the ends of the die and the exit termini 10 and 11 of the openings. It is pointed out that 35 because of the fact that the die openings are formed in the ends of the die which are provided with the inclined faces 5 and 6, the walls around the entrance or flared ends of the openings are elliptically fashioned and 40 the inner edges (meaning the edges toward the center of the body portion) extend to the junction of the inclined faces 5 and 6 with the faces 3 and 4 and from thence the edges of the inner walls of the die openings 45 are inwardly inclined both transversely and longitudinally upon curvilinear lines.

50 In practice, a suitable blank 17 is supported by means not necessary to describe here, with its longitudinal central line in alignment with the axis of one of the die openings and arranged with the body portion thereof at right angles with respect to the axis. A plunger 12 having a reduced end 13 and a shoulder 14 and arranged in alignment 55 with the axis of the die opening, is employed for forming the cotters from the blanks. In this operation the reduced end 13 of the plunger 12 constitutes a mandrel about which the eye of the cotter is bent and the shoulder 14 is arranged to constitute an abutment to engage the side of the cotter blank at its median portion and drive the blank through the die opening. The engagement of the portions of the blank on

65 opposite sides of the plunger with the inner opposing walls of the die opening causes the blank to be bent into proper form and at right angles with respect to the line of movement of the plunger so that after the exit 70 of the blank from the exit end of the die opening, the cotter operated upon is perfectly finished. In Fig. 5 is shown a cotter produced by a die such as is shown in Fig. 1 and is designated by the numeral 15.

75 I claim:—

1. A device for making cotters including a die comprising a body portion provided with an approximately cylindrical opening extending therethrough and terminating in an exit discharge end, and further provided 80 with a slot communicating with the exit end and extending to an outer face of said body portion, the side walls of said opening constituting means for bending a suitable blank at right angles to its line of movement 85 through said die during the forming operation in combination with a plunger adapted to fit and be guided by the cylindrical opening of the die and having at its forward end a reduced portion arranged to form a shoulder 90 against which the blank engages.

2. A device for making cotters including a die comprising a body portion in the general form of an obtuse rhombohedron, said body portion provided in the inclined faces 95 thereof with an approximately cylindrical opening having an outwardly flared entrance and extending therethrough and terminating in the exit or discharge end, and further provided with a slot extending from 100 an end of the body portion to and communicating with the exit or terminus of said opening, the side walls of said opening constituting means for bending a suitable blank at right angles to its line of movement 105 through said die during the forming operation in combination with a plunger adapted to fit and be guided by the cylindrical opening of the die and having at its forward end a reduced portion arranged to form a shoulder 110 against which the blank engages.

3. A device for making cotters including a die comprising a body portion in the general form of an obtuse rhombohedron, one of the inclined ends of said body portion provided with an approximately cylindrical opening, the entrance opening outwardly flaring and terminating at the junction of the inclined end, and one side face of the body portion and with the other or exit end 115 in one of the side faces thereof at a point removed from the end of the body portion, said end further provided with a slot extending to and communicating with the exit end of said opening, the side walls of said 120 opening and slot constituting means for bending a suitable blank at right angles to its line of movement while passing through 125

said die during the forming operation in my hand in presence of two subscribing witnesses.
combination with a plunger adapted to fit
and be guided by the cylindrical opening of
the die and having at its forward end a re-
duced portion arranged to form a shoulder
against which the blank engages.

In testimony whereof I have hereunto set

HOWARD H. SHELTON.
